UNITED STATES PATENT OFFICE.

GERHARD ZEILSTRA, OF GRAND RAPIDS, MICHIGAN, ASSIGNOR OF ONE-HALF TO NANCO ROSEMA, OF SAME PLACE.

BUNG.

SPECIFICATION forming part of Letters Patent No. 559,656, dated May 5, 1896.

Application filed November 2, 1895. Serial No. 567,702. (No model.)

To all whom it may concern:

Be it known that I, GERHARD ZEILSTRA, of Grand Rapids, in the county of Kent and State of Michigan, have invented a new and Improved Bung, of which the following is a full, clear, and exact description.

The object of the invention is to provide a new and improved bung, arranged for convenient insertion in and removal from a barrel or like vessel, and adapted to be securely locked in place to prevent leakage of the liquid or gases contained in the barrel or other vessel.

The invention consists principally of a fastening device provided with spring-yielding arms adapted to be spread and engage the inside of a barrel at the sides of the bung-hole, and a cam-lever for actuating said arms.

The invention also consists of certain parts and details and combinations of the same, as will be fully described hereinafter, and then pointed out in the claims.

Reference is to be had to the accompanying drawings, forming a part of this specification, in which similar characters of reference indicate corresponding parts in all the figures.

Figure 1 is a sectional side elevation of the improvement as applied and with the bung fastened in place. Fig. 2 is a similar view of the same with the bung unlocked. Fig. 3 is a plan view of the improvement. Fig. 4 is an inverted sectional plan view of the same on the line 4 4 of Fig. 1, and Fig. 5 is a similar view of the same on the line 5 5 of Fig. 2.

The improved bung A is preferably made of sheet metal and formed with a hollow conical body A', formed at its upper end with an outwardly-extending annular flange A², under which rests a packing-ring A³, of rubber or other suitable material, and adapted to engage the outside of the barrel around the bung-hole, as is plainly shown in Figs. 1 and 2.

In the base A⁴ of the bung A is arranged, centrally, a downwardly-extending bearing A⁵ for the upper end of a vertically-disposed rod B, provided on its upper end with an eye B', engaged by a cam-lever C, located within the body A', and adapted to draw the rod B upward in its bearing to lock the bung in place, as hereinafter more fully described.

On the lower end of the rod B is held a spreader D, preferably made with spring-arms D' and D², extending upwardly and outwardly, so as to form at their upper ends downwardly and inwardly extending guide-arms D³ and D⁴, respectively, engaging guides F' and F², formed on a keeper F, secured to the under side of the base A⁴ of the bung A. The arms D' D² of the spreader D normally extend at their upper ends beneath the base A⁴ of the bung, so that the latter can be conveniently inserted in the bung-hole with the rod B and spreader D extending inside of the barrel, as indicated in Fig. 2. Now when the rod B is in this position the cam-lever C is open, and when it is desired to lock the bung A securely in place and draw it tightly into the bung-hole then the operator swings the cam-lever C downward into the position shown in Fig. 1, whereby the rod B is drawn upward with the spreader D. This upward movement of the arms D' and D² of the spreader D causes the guide-arms D³ and D⁴ to slide in the guides F' and F², respectively, whereby the said arms D' D² are moved outwardly to engage the inside of the barrel on opposite sides of the bung-hole, and at the same time the bung A is firmly drawn downward, owing to the upper ends of the arms D' D² resting against the inside of the barrel.

In order to prevent leakage of the gases at the bearing A⁵, I provide the rod D with an annular offset or collar B², adapted to be seated on an elastic packing-ring G, held on the lower end of the bearing A⁵, said collar B² being firmly pressed in contact with the lower face of said packing-ring when the rod B moves into an uppermost position.

Now it will be seen that by the arrangement described the bung A is drawn very tightly into the bung-hole to prevent leakage, and at the same time the bung is securely locked in place to prevent accidental or other displacement. When it is desired to remove the bung, then the operator, by the use of a suitable tool, (see dotted lines 1,) simply swings the cam-lever C upward into the position shown in Fig. 2, so that the rod B is moved downward and the spreader-arms D' D² are caused by spring action to automatically

move inward toward each other to permit of removing the bung from the bung-hole by simply pulling upward on the cam-lever. C.

Having thus fully described my invention, I claim as new and desire to secure by Letters Patent—

1. A bung, provided with a fastening device, having a spreader provided with spring-yielding arms adapted to spread and engage the inside of the barrel at the sides of the bung-hole, and a cam-lever for actuating said arms, substantially as shown and described.

2. A bung, provided with a fastening device, comprising a rod fitted to slide in the bung, a cam for moving said rod up and down, and a spreader held on said rod and having spring-yielding arms adapted to spread and engage the inside of the barrel at the sides of the bung-hole, substantially as shown and described.

3. A bung, provided with a fastening device, comprising a rod fitted to slide in the bung, a cam for moving said rod up and down, a spreader held on said rod and having spring-yielding arms adapted to spread and engage

the inside of the barrel at the sides of the bung-hole, and guides for engaging said arms, to spread and close the same, substantially as shown and described.

4. A bung, provided with a fastening device comprising a rod fitted to slide in the bung and having a collar, a cam-lever for imparting movement to the said rod, and an elastic packing-ring held on the bearing for the said rod and adapted to be engaged by said collar, substantially as shown and described.

5. A bung, provided with a fastening device comprising a rod fitted to slide in the bung, a cam-lever for actuating said rod, a spreader held on said rod and provided with side arms formed with guide-arms, and a keeper held on the bung and provided with guides engaging said guide-arms, to open and close the spreader, substantially as shown and described.

GERHARD ZEILSTRA.
